UNITED STATES PATENT OFFICE.

OLIVER L. DOSCH AND MARTIN HEMLEB, OF ELIZABETH, NEW JERSEY, ASSIGNEES TO
THE SINGER MANUFACTURING COMPANY, A CORPORATION OF NEW JERSEY.

SEWING-MACHINE.

1,304,750.

Specification of Letters Patent. Patented May 27, 1919.

Application filed March 2, 1917, Serial No. 151,900. Renewed November 4, 1918. Serial No. 261,150.

To all whom it may concern:

Be it known that we, OLIVER L. DOSCH and MARTIN HEMLEB, citizens of the United States, residing at Elizabeth, in the county 5 of Union and State of New Jersey, have invented certain new and useful Improvements in Sewing Machines, of which the following is a specification, reference being had therein to the accompanying drawings.

- 10 In the usual flat-bed type of sewing machine head the loop-taker and feeding mechanisms are supported by bearing lugs projecting downwardly from the open under side of a flat bed-plate, while the presser-
15 foot, take-up and needle-actuating mechanisms are sustained by an overhanging bracket-arm carried by a vertical standard whose base is bolted or screwed to the upper or cloth-supporting side of the bed-plate.
20 Such a sewing machine head is commonly supported by a treadle or power-stand comprising a flat table-top which is apertured to receive the bed-plate and the downwardly projecting and exposed parts carried thereby; the upper or cloth-supporting surface of 25 the bed-plate being set flush with the upper surface of the table-top.

Among the disadvantages inherent in the 30 operation of machines of this type may be mentioned the necessity of disconnecting the driving belt and tilting the machine head rearwardly to afford access to the mechanism disposed below the bed-plate for purposes of inspection, cleaning, adjusting and 35 oiling. Being exposed below, any excess oil dripping from the lower mechanism becomes a source of annoyance, and, furthermore, the exposed bearing parts readily collect dust to the impairment of the efficiency of the machine. In manufacturing the frame of such 40 a machine, the bed-plate and the base of the standard must be carefully and very accurately machined to insure the correct relative positioning of the needle, the needle-hole in the throat-plate, and the loop-taker beak, when the machined parts and mechanism are 45 assembled.

The present improvement has for an object to provide a sewing machine which, 50 while having a flat rectangular cloth-plate adapted to be set flush with the table-top, will be free from the above and other disadvantages incident to the practical operation of flat-bed machines such as heretofore known.

A further object of the invention is to provide a machine in which the working parts below the cloth-plate may at all times be readily maintained in a properly lubricated condition, without disturbing the normal 60 operative position of the machine.

Further objects of the invention will appear from the following description and claims.

To the attainment of these ends, the machine frame, in its preferred embodiment, is formed preferably as a one-piece casting comprising a trough-shaped supporting bed from one end of which rises a standard carrying a bracket-arm which terminates in a 70 head disposed above the opposite end of the supporting bed. The bed is formed with inwardly projecting lugs, affording bearings for the feeding and loop-taker mechanisms, and with outwardly extending horizontal 75 lugs disposed above its bottom and affording supports serving to sustain the bed within the usual apertured table-top. A removable cloth-plate is provided to close the open upper side of the supporting bed and is formed 80 with bent over marginal portions which extend beyond and conceal the horizontal outwardly projecting supporting lugs above referred to. The cloth-plate is secured in position by suitable means and is cut away at 85 one end, to fit snugly about the base of the bracket-arm standard, while at its opposite end suitable guideways are provided within which a cover-plate for the loop-taker is 90 slidingly fitted. The cloth-plate is further 95 formed, adjacent said guideways, with an aperture adapted to fit about a rectangular throat-plate which is secured directly to inwardly projecting ledges carried by the side-wall portions of the supporting bed.

Preferably, a flat box-shaped oil-reservoir is sustained within the supporting bed by means of downwardly projecting delivery-tubes which are carried by said oil-reservoir and are removably received within upwardly 100 opening oil-holes formed in one of the inwardly projecting bearing lugs above mentioned. The oil-reservoir carries various other delivery-tubes which conduct oil to various moving parts or bearings requiring lubrication. The oil-receptacle and tubes leading therefrom may be filled with wicking material to suitably control the flow of oil.

In the accompanying drawings forming a part of this specification, Figure 1 is a per- 110

spective view of the machine showing the removable cloth-plate in dotted lines. Fig. 2 is a perspective view of the removable cloth-plate. Fig. 2^a is a cross-section on the line 5 *a*—*a*, Fig. 9. Fig. 3 is a side elevation of the machine partly in section. Fig. 4 is a plan view of the supporting bed and the mechanism contained therein; the standard being shown in section. Fig. 5 is a detail of 10 the feed-adjusting screw. Fig. 6 is a vertical cross-section on the line 6—6, Fig. 4. Fig. 7 is a transverse vertical section on an enlarged scale through the supporting bed; the oil receptacle being removed. Fig. 8 is a 15 similar view with the oil-receptacle in position and Fig. 9 is a plan view of the forward end of the supporting bed with the oil-receptacle in position.

In the preferred form of the invention, as 20 illustrated, the machine-frame consists of a one-piece casting having a substantially horizontal trough-shaped supporting bed 1 which, at one end, supports the vertical standard 2 carrying the tubular bracket-arm 3 terminating in the usual hollow head 4. The trough-like bed 1 supports the entire machine-head to be described and is in turn supported by means of the rearwardly projecting horizontal bed-supporting lugs 5, 5 25 and forwardly projecting lugs 6, 6, all of which are disposed above the bottom of the bed 1 and preferably just below the horizontal plane defined by the open upper side of the bed 1. The lugs 5, 5 are bored out 30 to receive the usual hinged pins 7, 7 each of which is pivoted at 8 to a metal block 9 which is set flush with the table-top *t* in a manner well-known. The lugs 6, 6 are adapted to rest upon the usual ledge 10, Fig. 40 7, which is disposed below the upper surface of the table-top *t* and is common to treadle-stands of the well-known family-machine type.

Journalized within the hollow head 4 is the 45 presser-bar 11 and reciprocating needle-bar 12 which is actuated through the usual link 13 by a crank carried at the forward end of the rotary main-shaft 14 to whose opposite end is secured the combined hand- and pulley-wheel 14'. Secured to the main-shaft 14 is a bevel-gear 15 which meshes with a 50 duplicate gear 16 secured to the upper end of a vertical shaft 17 journalized in the inwardly extending bearing lugs 18, 18. A bevel-gear 19, secured to the lower end of 55 the shaft 17, transmits rotary motion to a duplicate gear 20 fixed to the lower horizontal shaft 21 which extends within and lengthwise of the supporting bed 1 and is 60 journalized in the inwardly projecting bearing lugs 22 and 23 carried by and preferably formed as a part of said bed. To the forward end of the lower shaft 21 is secured a bevel-gear 24 of double the size of the companion gear 25 fixed to the short vertical 65

shaft 26 which is journaled in the bushing 27 and at its upper end carries the rotary hook mechanism *h*, the construction of which is disclosed in my prior Patent No. 1,149,049, of August 3, 1915. The bushing 70 27 is fixed within a suitable aperture formed in the inwardly projecting bearing lug 28 carried by the bed 1.

The feeding mechanism is housed within the trough-shaped bed 1 and comprises the 75 feed-dog 7 carried by the feed-bar 30 which at its forward end is formed with a horizontally elongated boss 31, Figs. 4 and 9, whose opposite ends are countersunk to receive the pointed ends of the pivot pins 32, 32 carried by the upwardly extending arms 33, 33 of the feed-rocker 34 which is supported on pointed pivot-pins 35, 35 carried by the frame. The upper side of the elongated boss 31 is flattened and grooved 80 axially at 36 to receive and conduct oil to the pivot-pins 32, 32. The feed-rocker 34 further comprises a crank-arm 37 which is pivotally connected at 38 to one end of a link 39 whose opposite end is connected by 90 a pivot-pin 40 to the lower end of a short link 41 whose upper end is pivotally connected to the arm 42 of the feed-adjusting rocker 43, which is pivotally mounted upon pointed pivot-pins 44, 44, Fig. 4 carried by 95 the frame. One end of the pivot-pin 40 carries a roller 45, Fig. 9, entering the curved slot 46 formed in the rocker 47 carried by the fulcrum-shaft 48 which is journaled in the bearing lug 22. The rocker 47 is provided with a yoke 49 which embraces the feed-advancing eccentric or cam 50 fixed to the shaft 21.

The feed-lifting mechanism comprises an eccentric 51, Fig. 7, fixed to the shaft 21 and 100 embraced by the strapped end of a pitman 52 whose opposite end is pivoted at 53 to the lower end of the crank-arm 54 whose upper split-socketed end is clamped about one end of a short horizontal fulcrum-shaft 55 which 110 is journaled in the inwardly extending bearing boss 56 carried by the supporting bed 1. Fixed to the other end of the shaft 55 is a feed-lifting arm 57 whose free end carries a roller 58 adapted to sustain the rearwardly 115 extending free end of the feed-bar 30. A spring 59, attached at its upper end to the feed-bar and at its lower end to an extension 60 of the arm 57, serves to maintain the feed-bar in contact with the roller 58. 120

The feed-adjusting rocker 43 serves to shift the working position of the pin 40 relatively to the fulcrum 48 of the rocker 47 and is actuated to shift the pin 40 by means of the feed-adjusting screw 61, Figs. 4 and 125 5, sustained within the bed 1 and formed with a square thread 62 which acts, when the screw is turned, to raise or lower the pin 63 carried at the free end of the arm 64 of the feed-adjusting rocker 43. The side-wall 130

portion of the bed 1 adjacent the screw 61 is apertured to receive a spring-pressed retaining pin 65 which is adapted to snap into any one of the series of peripheral notches 5 66 formed at the lower edge-portion of the head 67 of the screw 61. The pin 65 carried by the head 67 serves to prevent the screw being turned more than one complete revolution.

10. A detachable cloth-plate 70 is provided to tightly close the open upper side of the trough-like supporting bed 1 and afford a suitable supporting surface for the work being stitched. This plate is rectangular in 15 form and is preferably punched out of sheet metal; the peripheral portion being bent over as shown at 71 to stiffen the plate and give it a thickened appearance. As will be clear from Figs. 1 and 2, one end of the plate 20 70 is cut away at 72 to snugly embrace the base of the standard 2 and is apertured at 73 to fit over the head 67 of the feed-adjusting screw 61. The front end of the plate 70 is provided with parallel guideways 74, 74 25 within which the usual cover-plate 75 for the loop-taker is slidingly fitted. A spring 75' secured to the cover-plate 75 acts to hold the latter in contact with the guideways 74, 74. The plate 70 is further apertured at 76 to 30 fit about the rectangular throat-plate 77 which is screwed to the top surface of the inwardly extending ledges 78, 78 formed on the bed 1. Suitably disposed screws 79 serve to secure the cloth-plate 70 to the bed 35 1. It will be noted that the cloth-plate is wide enough to entirely cover and practically conceal the bed-supporting lugs, thus giving the machine a neat and finished appearance.
40. The lower mechanism is lubricated by means of oil which is distributed to the various bearing parts from a flat, box-shaped, oil-reservoir 80, which is supported within the bed 1 by means of a pair of spaced vertically disposed delivery-tubes 81, 82, fixed to and extending downwardly from the reservoir 80. The tubes 81, 82 fit into corresponding oil-holes 83, 84 drilled into the bearing boss 22 and leading to the shafts 21 45 and 48, respectively. Various other delivery-tubes 85, carried by and radiating in different directions from the reservoir 80, conduct oil to the several other bearings requiring lubrication. The reservoir 80 and 50 delivery-tubes 81, 82 and 85 are filled with suitable wicking material 86 which acts to control the flow of oil through the delivery-tubes. The wicking material projects from the free ends of the delivery-tubes and said 55 60 projecting portions are adapted to wipe over the various oil-holes to which the lubricant is to be conducted, thus acting to slowly supply the lubricant to the several bearing parts. The cover of the receptacle 80 is provided with an oil-receiving aperture 87

which registers with a supply aperture 88 in the cloth-plate 70, Fig. 8.

By constructing the machine in the manner described it is rendered dust proof and the heretofore exposed lower mechanism is 70 tightly incased. Moreover, any excess oil dripping from the working parts will be caught by the supporting bed from which it cannot escape. It is desirable, although not essential, that the casting for the frame be 75 formed in one piece for the reason that, when so formed, all the bearing apertures may be drilled in one operation by a suitable automatic drilling and reaming machine. When the working parts are assembled in 80 the frame, the needle will accurately register with the needle-hole in the throat-plate and will be properly spaced from the point of the loop-taker beak. The heretofore time-consuming operation of accurately fitting the 85 bracket-arm to the supporting-bed is thus obviated and precision in the positioning of the co-operating stitch-forming elements is assured.

Should the cloth-plate of the present machine become marred or otherwise damaged, it may be readily removed for repair or replacement by a new one.

In the present machine the problem of 90 oiling the lower mechanism is greatly simplified as it is unnecessary to stop the machine, remove the belt and tilt the machine-head rearwardly to expose the lower bearing parts for lubrication. With the present construction it is merely necessary to supply a 100 small quantity of oil to the reservoir 80 through the oil-hole in the cloth-plate. This may obviously be done without disturbing the position of the machine-head.

While the preferred form of the invention 105 has been shown and described, it is to be understood that its essential elements of construction are susceptible of material modification within the scope of the invention.

Having thus set forth the nature of the 110 invention, what we claim herein is:

1. A sewing machine frame comprising an open topped trough-shaped supporting bed, a standard fixed directly to and carried by one end-portion of said supporting bed, and a bracket-arm carried by said standard and overhanging said supporting bed.

2. A sewing machine frame comprising an open topped trough-shaped supporting bed having laterally extending bed-supporting lugs, a standard fixed directly to and carried by one end-portion of said supporting bed, and a bracket-arm carried by said standard and overhanging said supporting bed.

3. A sewing machine frame comprising a trough-shaped supporting bed having bed-supporting means disposed above the bottom of said bed, a standard fixed directly to and carried by one end-portion of said bed.

- and a bracket-arm carried by said standard and overhanging said bed.
4. A sewing machine frame comprising a trough-shaped supporting bed, a standard 5 fixed directly to and carried by one end portion of said supporting bed, a bracket-arm carried by said standard and overhanging said supporting bed, and a detachable cloth-plate serving to close substantially the 10 entire upper side of said bed.
5. A sewing machine frame comprising a trough-shaped supporting bed, a standard carried by and rising from one end of said supporting bed, a bracket-arm carried by 15 said standard and overhanging said supporting bed, and a detachable cloth-plate serving to close the upper side of said bed, said cloth-plate being cut away at one end to embrace the base of said standard.
- 20 6. A sewing machine frame comprising a trough-shaped supporting bed having lateral bed-supporting means, a standard carried by and rising from one end of said supporting bed, a bracket-arm carried by said standard 25 and overhanging said supporting bed, and a detachable cloth-plate of larger size than the open top of said trough-shaped supporting bed and adapted to close the upper side of said bed and conceal said bed-supporting 30 means.
7. A sewing machine frame comprising an open-topped trough-shaped supporting bed, standard and bracket-arm, all cast in one piece, and a cover-plate wider than said bed 35 and serving to close the open upper side of the latter.
8. A sewing machine comprising, a frame formed with a trough-shaped supporting bed, a standard rising from one end of said bed, a bracket-arm carried by said standard, stitch-forming and work-feeding mechanisms incorporated in said frame and including moving elements supported directly by and within said trough-shaped bed.
- 45 9. A sewing machine comprising, a frame formed with a trough-shaped supporting bed, a standard carried by and rising from one end of said bed, a bracket-arm carried by said standard, a cloth-plate wider than 50 said bed and closing substantially the entire open upper side of the latter, stitch-forming and work-feeding mechanisms incorporated in said frame and including moving elements supported directly by said bed independently of said cloth-plate.
- 55 10. A sewing machine comprising a frame formed with an open-topped trough-shaped supporting bed having inwardly projecting bearing lugs, a standard supported by and rising from one end of said bed and a 60 bracket-arm carried by said standard, stitch-forming and work-feeding mechanisms incorporated in said frame and including moving parts journaled in said bearing lugs, and a cover-plate serving to close the upper 65 side of said supporting bed.
11. A sewing machine comprising a frame having a trough-like supporting-bed, a standard supported by said bed and rising from one end thereof, a bracket-arm carried by 70 said standard, stitch-forming and work-feeding mechanisms incorporated in said frame, and a detachable cloth-plate wider than said bed and serving as an upper closure therefor.
- 75 12. A sewing machine comprising a trough-shaped supporting bed, bearing lugs fixed directly to and disposed within the hollow of said bed, a standard supported by and rising from one end of said bed, a bracket-arm carried by said standard, stitch-forming mechanism including a loop-taker actuating shaft journaled in certain of said lugs within said bed, feeding mechanism supported within said bed by others of said lugs and 80 actuated by said shaft, and a detachable cloth-plate serving as an upper closure for 85 said bed.
13. A sewing machine comprising a frame formed with a trough-shaped supporting 90 bed, stitch-forming and work-feeding mechanism incorporated in said frame and including moving parts housed within said bed, a detachable cloth-plate serving as an upper closure for said bed, an oil-reservoir 95 disposed within said bed and having an oil-receiving opening in its upper side, and delivery-tubes leading from said reservoir to said moving parts, said cloth-plate being formed with an oil-supply opening which 100 registers with the oil-receiving opening in said receptacle.
14. A sewing machine comprising a frame formed with a trough-shaped supporting bed, stitch-forming and work-feeding mechanisms incorporated in said frame and including moving parts housed within said bed, and a removable oiling device supported within said bed, said oiling device including an oil-reservoir and delivery-tubes 105 carried thereby, said delivery-tubes being adapted to conduct oil to various of the moving parts requiring lubrication.
- In testimony whereof, we have signed our names to this specification.

OLIVER L. DOSCH.
MARTIN HEMLEB.
